ILLUMINATING DEVICE

David I. Critoph and Henry S. Schrader, Buffalo,
and Oscar W. Richards, Snyder, N. Y., assign-
ors to Spencer Lens Company, Buffalo, N. Y.,
a corporation of New York

Application April 13, 1940, Serial No. 329,462

3 Claims. (Cl. 240—47)

This invention relates to illuminating devices and more particularly to new and improved illuminating device which will be cooler during use.

One of the objects of the invention is to provide a new and improved illuminating device of the character set forth.

Another object of the invention is to provide a new and improved device of the character set forth which will be cooler during use allowing the adjustment of the device to desired position.

Another object of the invention is to provide new and improved means for ventilating the interior of such a device to prevent its overheating during its use.

Another object of the invention is to provide simple, efficient and economical means for ventilating and cooling an illuminating device.

Another object of the invention is to provide new and improved reflector adjusting means for illuminating means.

Another object of the invention is to provide a new and improved illuminating device wherein the parts may be quickly and easily assembled or disassembled.

Another object of the invention is to provide new and improved adjusting means for illuminating means.

Other objects and advantages will be apparent from the following description taken in connection with the accompanying drawings. It will be understood that many changes may be made in the details of construction and arrangement of parts without departing from the spirit of the invention as expressed in the accompanying claims. We, therefore, do not wish to be limited to the exact details shown and described as the preferred form has been shown by way of illustration only.

Referring to the drawings:

Fig. 1 is a side elevation of one form of the invention;

Fig. 2 is a front view of the form shown in Fig. 1;

Fig. 3 is a sectional view taken on line 3—3 of Fig. 2;

Fig. 4 is a sectional view taken on line 4—4 of Fig. 3, looking in the direction of the arrows;

Fig. 5 is a sectional view taken on line 5—5 of Fig. 3, looking in the direction of the arrows;

Fig. 6 is a sectional view taken on line 6—6 of Fig. 3, looking in the direction of the arrows;

Fig. 7 is a sectional view taken on line 7—7 of Fig. 3, looking in the direction of the arrows;

Fig. 8 is a side view, partly in section of a modified form of lens supporting housing;

Fig. 9 is a front view of the housing shown in Fig. 8;

Fig. 10 is a side elevation of another form of the invention;

Fig. 11 is a front view of the form shown in Fig. 10;

Fig. 12 is a sectional view taken on line 12—12 of Fig. 11; and

Fig. 13 is a sectional view taken on line 13—13 of Fig. 12, looking in the direction of the arrows.

In the construction of illuminating devices to be employed for such purposes as to provide illumination for microscopes, it is necessary that the device be moved to adjust the light projected therefrom into desired focus and adjustment with the instrument. To do this it is necessary to touch the illuminating device with the hands and it is therefore important that the device be so constructed that it will be as cool as possible and not be too hot to adjust with the hands during use. It is therefore the primary purpose of this invention to provide an illuminating device of the type set forth which will be cool enough during use that it may be adjusted and focused to desired position without burning the hands.

Referring more particularly to the drawings wherein similar reference characters designate corresponding parts throughout the several views, the form of the device shown in Figs. 1, 2 and 3 comprises a base 1 on which are the pivot ears 2 and pivot 3. Pivoted on the pivot 3 is the lamp-house support 4 which is adapted to be adjusted to desired angular position by means of the screw 5 having the thumb wheel 6 and ball joint 7 so that by turning said thumb wheel 6 the lamphouse may be adjusted to desired angular relation with the base 1.

On the support 4 is the lamphouse 8 comprising the rear housing or portion 9 and front housing or portion 10. The rear portion 9 carries the lamp socket 11 carrying the lamp 12, the switch 13 which is connected in one line 14 of the current which then continues to the socket 11 and the other line 15 of which is secured directly to the lamp socket 11.

The rear housing 9 also carries the reflector 16 which is supported by the support 17 and may be adjusted by turning the adjusting screw 18.

Over the lamp 12 is secured the chimney member 19 having the opening 20 to allow light from the lamp to be projected. This chimney 19 is secured in position by the screws 21, and is open at its bottom surrounding the base of the lamp and has the light deflecting members 22 at its

upper end to prevent the light from escaping but allowing a current of air to enter at the bottom and pass through said chimney member 19 and to escape between the deflecting members 22.

The rear housing 9 also has the set screws 23 which are adapted to enter slots 24 adjacent the edges of the rim 25 on the front housing 10 whereby the rear housing 9 may be secured in operative position by then tightening the said screws 23.

The front housing 10 comprises a light trap ventilating ring 47 and the extending portion 25 containing the objective lens system 26 and holder therefor 27 which is adapted to be adjusted so as to focus the light emanating from the lamp 12 by the rack 28 and pinions 29 which may be adjusted by rotating either of the thumb wheels 30.

The interior of the device is formed so as to have a medium bright bare metal finish. The exterior of both the front housing 10 and rear housing 9 are provided with fins 31, which are preferably finished in dull black, although it has been found preferable in the commercial construction to finish the exterior in a black crinkled finish.

The number of said fins 31 must be balanced to the thickness of the fins, thickness of the lamphouse and diameter thereof. The fins increase the radiating area of the surface and when they are spaced properly allow air to circulate between them.

If desired the front housing 10 may be provided with only one lens focusing knob or with a knurled adjusting ring 32 as shown in Figs. 8 and 9.

In the form of the invention shown in Figs. 10, 11, 12 and 13, the base 33 supports the adjustable stand 34 to the upper end of which is secured the illuminating device.

The illuminating device comprises the rear housing 35 and the front housing 36. The rear housing 35 is secured at its forward end by the screw or the like 37 to the support and the rear portion of the front housing is adapted to frictionally engage the front end of the rear housing to retain the parts in assembled relation.

On the rear housing 35 is the lamp socket 48 supporting the lamp 38 and adapted to be retained in operative position in the housing by the set screw 39. The socket 48 has the ventilation grooves or openings 40, circumferential thereof to allow air to enter the body of the lamp through said openings 40 and then pass through the housing 35 between the lamp 38 and the walls of the portion 35 and then be exhausted through the circumferential light trap ventilating ring 41.

The front housing 36 contains the focusing lens system 42 adapted to be adjusted to focus the light by turning the knurled ring 43 which through the slot 44 and set screw 45 causes the lens system to move to focus the light.

Adjacent its forward end, the rear housing member has the slots 46 which are in alignment with the light trap ring 41.

In this form the rear and front housings are also provided on their inner surfaces with a medium bright bare metal finish and on their outer surfaces with dull black or black crinkle finished fins as stated above for the other form of the invention.

It has been found that with the ventilation arrangements as shown and described and with the inner surface of the housings of a medium bright bare metal finish combined with the dark fins on the exterior of the housing that an illuminating device may be constructed which will be much cooler in operation than was possible with prior art structures.

In view of the above it will be seen that we have provided simple, efficient and economical means for obtaining all of the advantages of the invention.

Having described our invention we claim:

1. In a device of the character described, a rear housing, a lamp in said rear housing, a front housing in alignment with said rear housing, a lens system in said front housing in optical alignment with said lamp, the interior surface of both of said housings having a medium bright metal finish and the exterior of said housings having a plurality of fins, said exterior being of a dark color, and an overhanging flange adjacent the edge of one of said housings and spaced from an overhanging an opening in the other of said housings to allow ventilation of the interior of said housings.

2. In a device of the character described, a rear housing having an opening adjacent its forward end, a lamp in said rear housing, a front housing in alignment with said rear housing, a lens system in said front housing in optical alignment with said lamp, the interior surface of both of said housings having a medium bright metal finish and the exterior of said housings having a plurality of fins, said exterior being of a dark color, and an overhanging flange adjacent the edge of one of said housings and spaced from an overhanging an opening in the other of said housings to allow ventilation of the interior of said housings.

3. In a device of the character described, a rear housing having diametrically opposed openings adjacent its forward end, a lamp in said rear housing, a front housing in alignment with said rear housing, a lens system in said front housing in optical alignment with said lamp, the interior surface of both of said housings having a medium bright metal finish and the exterior of said housings having a plurality of fins, said exterior being of a dark color, and an overhanging flange adjacent the edge of one of said housings and spaced from an overhanging an opening in the other of said housings to allow ventilation of the interior of said housings.

OSCAR W. RICHARDS.
